(57) **CLAIM**

The ornamental design for a mobile energy storage power supply unit, as shown and described.

DESCRIPTION

1. Mobile energy storage power supply unit

1.1 : Perspective

1.2 : Front

1.3 : Back

1.4 : Top

1.5 : Bottom

1.6 : Left

1.7 : Right

Fig. 1.1 is a perspective view of a mobile energy storage power supply unit(PowFi700W); fig. 1.2 is a front view thereof; fig. 1.3 is a back view thereof; fig. 1.4 is a top view thereof; fig. 1.5 is a bottom view thereof; fig. 1.6 is a left view thereof; fig. 1.7 is a right view thereof.
